UNITED STATES PATENT OFFICE.

ERNEST WHITWORTH, OF LOWELL, MASSACHUSETTS.

DESIGN FOR A BICYCLE-FRAME.

SPECIFICATION forming part of Design No. 27,308, dated July 6, 1897.

Application filed August 13, 1896. Serial No. 602,674. Term of patent 7 years.

To all whom it may concern:

Be it known that I, ERNEST WHITWORTH, a citizen of the United States, residing at Lowell, in the county of Middlesex and State of Massachusetts, have invented and produced a new and original Design in Bicycle-Frames, of which the following is a specification, reference being had to the accompanying drawing, which discloses in perspective a bicycle-frame embodying my design.

The numeral 1 designates the lower-line tube, 2 the upper-line tube, and 3 the steering-head, of a bicycle-frame. Back braces are shown at 4 and 5, and 6 and 7 represent the members of the lower rear fork.

The king-post or tube is shown at 8. The lower portion of the post is formed into a truss

9, comprising two members which extend downwardly and then are curved forwardly until they meet the crank-bracket 10. At 11 and 12 are shown curved braces which extend upwardly from the members 6 and 7 of the lower rear fork and connected to the members of the truss 9.

The leading feature of my design consists of the curved truss 9 and the curved braces 11 and 12.

What I claim is—

The design for a bicycle-frame, substantially as herein shown and described.

ERNEST WHITWORTH.
